CONTROL APPARATUS FOR RADIO RECEIVERS

Alexander W. Plensler, Chicago, Ill., assignor to
 Belmont Radio Corporation, a corporation of
 Illinois

Application September 13, 1938, Serial No. 229,728

16 Claims. (Cl. 74—10)

My invention relates in general to control apparatus, and more in particular to control apparatus of the so-called automatic type for tuning radio receivers. The present application is a continuation in part of my copending application, Serial No. 170,070, filed October 20, 1937, now Patent No. 2,130,153, issued September 13, 1938.

In both electrically operated and mechanically operated control apparatus, and particularly in such apparatus for radio receivers, a very satisfactory control structure has been employed wherein a plurality of control members such as discs, cams, and the like, are mounted upon a rotary shaft in predetermined angular control positions. The control members are normally retained on the shaft under frictional pressure against angular movement relative to the shaft, but such pressure may be varied so as to permit angular adjustment of a control member relative to the shaft when the pressure is decreased.

Various means have been disclosed for varying such frictional pressure on the control members including the structure of the above noted copending application. This structure has proven very satisfactory commercially. Additional means, however, will be disclosed herein which comprises other satisfactory solutions of the general problem of setting and retaining control members at predetermined control positions. The structure of the present invention may be adopted to control apparatus utilizing the cam and lever elements of the device of the copending application as well as to many other types of control apparatus.

According to the present invention, structure is provided whereby the tuning means for a radio receiver may be manually operated and the frictional pressure on the control members associated with such means varied, not only from a position adjacent the side wall of a radio receiver cabinet in which the control apparatus is installed, but also from the front, and even from the rear of the radio receiver cabinet.

In control apparatus of the general type described above, and wherein manually movable rods, levers, or the like have been employed to mechanically move the control members on a rotary shaft, such rods, levers, or the like, normally were spring pressed and returned to their original idle position immediately after the operator's finger was removed, and the tuning operation completed. As a result it was only by being able to associate the dial or tuning scale indication with the particular station to which

the operator was listening, that the operator could subsequently tell what particular station he had tuned in. In the present invention I provide latching means associated with the frictional pressure varying and manually tuning structure to retain a manually movable rod, lever, or the like in an operative position so as to contrast it with the remainder of such elements in idle position. Such a position is retained until another such element is operated to change the tuning position of the apparatus.

One of the objects of the present invention is to provide simplified, relatively inexpensive, and sturdy control apparatus wherein the control members therefor may be frictionally retained in predetermined control positions, and the frictional pressure thereon varied without the use of extraneous tools from any position about the cabinet or the like for such apparatus.

Other objects, features, and advantages of my invention will be apparent from the following description taken with the drawings in which:

Fig. 1 is a top plan view of the complete control apparatus, with the tuning condenser for a radio receiver associated therewith shown in a fragmentary portion.

Fig. 2 is a cross-sectional view along the lines 2—2 of Fig. 1 and looking in the direction of the arrow on such line, showing the manually movable control lever in idle position.

Fig. 3 is a view similar to that of Fig. 2 showing the structure of Fig. 2 with the lever in a latched indicating position after completing a tuning operation.

Fig. 4 is a detailed view of a fragmentary portion of the control apparatus of Fig. 1 showing the friction varying and manual tuning structure in a longitudinal cross-section. The structure is illustrated in a position for varying the pressure on the control members for the apparatus.

Fig. 5 is a view similar to that of Fig. 4 showing substantially the same structure in idle position in which neither the friction can be varied nor the tuning condenser manually operated.

Fig. 6 is a fragmentary cross-sectional view looking toward the left in the illustration in Figs. 4 and 5 with the large tuning wheel removed, but showing the structure in position to permit manual rotation of the tuning shaft over the entire tuning range.

Fig. 7 is a fragmentary detailed view partly in section of a modified embodiment of the structure for varying the frictional pressure on the control members of the apparatus of Fig. 1.

Fig. 8 is a cross-sectional view of a further modification of frictional pressure varying structure for use with the control member structure of Fig. 1.

Fig. 9 is a fragmentary view partly in section of a still further modification of frictional pressure varying structure for use with the control member structure of Fig. 1.

The control apparatus of the present invention includes a frame having a pair of end plates 10 and 11 which are mounted on a radio receiver chassis, or other similar apparatus. A variable condenser 12 for the radio receiver is supported from the frame plate 10 and utilizes the rotary shaft 13 for the control apparatus, or is coupled thereto in any desired manner. A plurality of control members 14 are likewise carried on the shaft 13. The control members 14 as illustrated comprise heart-shaped cams. It is understood, however, that many other configurations for both mechanical and electrical apparatus may be similarly mounted upon a rotary control shaft to be used with the structure of the present invention as will be apparent hereinafter. Each member 14 is rotatable with reference to the shaft 13, but is normally retained against rotation by means including friction washers 16 which are axially movable upon the shaft 13 but keyed against rotation by means of a projection 17 carried in a keyway 18 in the shaft. A friction washer 16 is supported on each side of each control member 14 in frictional engagement therewith. Intermediate the washers 16 are sleeves 19 which are both axially slidable and rotatable upon the shaft 13. The entire assembly of control members, friction washers, and sleeves, can move axially on the shaft and be compressed to increase the frictional pressure on the members therein, or it will open up to decrease the frictional pressure on each control member 14. A stop such as 21 secured to the shaft 13 at the left-hand end, as viewed in Fig. 1, acts to limit the movement to the left of such assembly by frictional pressure varying means at the right-hand end.

At the right-hand end of the axially slidable assembly, a spring washer 22 is normally carried intermediate a pair of friction washers 16, with a sleeve 19' adjacent thereto and in engagement with the outside friction washer. An internally threaded bushing 23 is in engagement with the sleeve 19' and is threadably adjustable axially on the shaft 13 to compress the control member assembly when adjusted to the left, as viewed in Fig. 1, or permit it to open up upon movement to the right with the consequent reduction in frictional pressure on the control members 14 in the assembly.

The threaded bushing 23 is adjusted by means of a crown gear 24 rigidly secured to a sliding sleeve 23' keyed to said bushing against rotation, but slidably axially relative thereto. This sliding connection causes the gear 24 to remain in engagement with a pinion gear 26. The gear 24 is, of course, rotated by the pinion gear 26 secured to a shaft 27. The shaft is rotated by a knob 28 at the outer end thereof, and available at the outside of the front wall 29 (Fig. 1) of the radio receiver cabinet. Rotatably supported on the shaft 27 is a toothed gear 31 which is retained against axial movement by a collar 32 secured to the shaft 27 on one side of the gear and a shoulder cut in the shaft on the other side of the gear. A stamped-out tuning wheel 33 is secured rigidly on a bushing 34 which in turn

is secured to the shaft 13 against movement by means of a set screw 36 or the like. The tuning wheel is employed to rotate the shaft 13 for ordinary normal tuning. A plurality of radially extending openings 37 (Fig. 2) are cut in the substantially cup-shaped rim of the wheel 33 with a strap portion 38 remaining in the body of the rim intermediate each two perforations.

Frictional pressure is exerted on the control members 14 in order to hold them against angular movement on the shaft 13, and the pressure is decreased or removed in order to permit an angular adjustment of the control members to predetermined control positions as will be hereinafter described. When it is desired to vary the frictional pressure on the control members 14, the tuning knob 28 is pulled outwardly from the position shown in Fig. 5 to the position shown in Fig. 4. In the latter position one of the teeth of the gear 31 slides into an opening 37 in the wheel 33 so that a strap portion 38 on each side of the opening rests in the usual two cavities, one on each side of the tooth of the gear. At the opposite side of the gear 31, and during the outward movement of the knob 28 and the associated shaft 27, the gear is positioned so that a pair of teeth in the same straddle a lug 39 extending at right angles to a bracket 41 integral therewith (Fig. 6) which is secured to the outside of the frame plate 11. Inasmuch as the bracket 41 is rigid and the gear 31 is rigidly retained thereon, the wheel 33 is maintained rigidly with reference to the gear 31 as a result of the holding connection between the wheel and gear.

As is clear from Fig. 4, when the gear 31 is pulled into locking position with the wheel 33 to thus maintain the shaft 13 rigid, the pinion gear 26 is also pulled into mesh with the teeth 40 on the crown gear 24. The shaft 27 rotates in the gear 31 and upon rotating the knob 28 clockwise or counterclockwise, depending upon whether it is desired to increase or decrease the frictional pressure on the control members 14, 45 the pinion gear 26 is rotated to move the crown gear 24 therewith. The latter secured to the threaded bushing 23 threadably adjusts such bushing to the left as viewed in Figs. 1 and 4, for instance, to increase the frictional pressure 50 on the control members 14 or threadably adjusts the bushing 23 to the right to permit the assembly of control members, washers, and sleeves, to open up and thus decrease the frictional pressure on the control members 14. With the frictional pressure on the control members decreased 55 the angular position of one or more of such control members may be changed with respect to the shaft 13, to thus set a selected member in a position corresponding to a predetermined tuning position of the variable condenser 12 for 60 the radio receiver.

In order to obtain the desired tuning position for the variable condenser 12, to subsequently position a control member, it is necessary to rotate the shaft 13 until the desired tuning is attained. This is accomplished by pressing the control knob 28 and the shaft 27 therewith from the locked position of Fig. 4 inwardly through the intermediate idle position illustrated in Fig. 5, 65 and then to the manual tuning position as illustrated in Figs. 1 and 6. With the knob 28 and shaft 27 in this position a rubber disc 44 secured to a beveled metal disc 46, which in turn is rigidly mounted on the shaft 27, engages a beveled flange 70 47 on the rim of the tuning wheel 33. In this

position the toothed gear 31 is out of locking position with the wheel 33, and the pinion gear 26 is out of mesh with the crown gear 24. The wheel 33 secured to the shaft 13 is thus free to turn and be driven by the rubber disc 44 which frictionally engages the flange 47 as the operator rotates the knob 28. Locking means are provided to hold the disc 44 in this position of engagement so that it is not necessary for the operator to continue to push inwardly on the knob 28. This locking means will be more fully described hereinafter. The control apparatus has the usual indicating dial associated therewith, and the desired position of the variable condenser 12 can be ascertained from such dial.

When the variable condenser 12 is in a desired predetermined position, and consequently the shaft 13 in a corresponding desired angular position, the setting operation for the control apparatus may be carried out and the control members 14 may each be individually adjusted in turn on the shaft 13 to correspond to a predetermined tuning position of the condenser 12. This is accomplished by depressing a lever 50 having a finger button 51 at the end thereof available on the outside of the cabinet. The levers 50 correspond in number to the control members 14 and are rotatably supported upon a rigid shaft 52 carried in the frame end plates 10 and 11. The selected lever 50 is depressed until the roller 53 on the inside end thereof engages the surface of a corresponding cam or control member 14, and then by continued movement of the lever the control member is rotated on the shaft 13 until the roller 53 is seated in the cavity 54 in the control member. In the meantime the operator holds the knob 28, and thus holds the shaft 13 against movement so that the predetermined tuned position of the condenser 12 is retained. After the angular adjustment of the control member 14, the lever 50 is returned to idle position and the same procedure may be followed with each of the control members 14. Normally enough frictional pressure will remain on each of the control members 14 even with the bushing 23 in its non-friction position so that each control member 14 will retain its set position while the same procedure is followed for the other members.

After all, or any desired number of the control members 14 have been set to the desired tuning position, the knob 28 may again be pulled outwardly to the position shown in Fig. 4 and the frictional pressure on the control members increased by rotating the knob in a friction increasing direction. When this operation is completed the knob 28 and shaft 27 are pressed inwardly to the idle position illustrated in Fig. 5, and the shaft 13, with the control members 14 rigid thereon, can be automatically rotated to predetermined tuning positions for the condenser 12 by depressing buttons 51 and the levers 50 therewith for engagement with the control members to rotate the same until a roller 53 seats in a cavity 54 as previously described.

Of course, the tuning condenser 12 can be adjusted to only a single broadcast station at a single time. Consequently only a single control unit comprising a control member 14 and lever 50 is operated at one time. Each lever 50 is retained on the shaft 52 by means of a hairpin spring 56 (Figs. 2 and 3) and this spring also acts to normally return the lever 50 to the idle position shown in Fig. 2. In accordance with the usual practice a station identification tab may

be provided for each button corresponding to the tuned position of the control member 14 therewith. As mentioned above, when the button 51 on a lever 50 is in idle position, it appears the same as all of the remaining buttons and levers, and it is therefore impossible to ascertain from an inspection of the buttons as to which broadcast station is being received. In order to indicate the station to which the control apparatus has just tuned the condenser, latching means are provided which comprise a substantially U-shaped bar 57 pivotally supported on the end plates 10 and 11 at a point indicated by the reference character 58. A coiled spring 59 is secured at one end to a rod 61 and at the other end to the latching bar 57 to pull the same downwardly against the top edge of the lever 50 as shown in Fig. 2. The bar 57, in idle position, rests at the bottom of a beveled edge on a projection 62 integral with the lever 50. The inside edge, or the edge toward the control member 14, for each projection 62 is straight and provided at such an angle that when in latched position as shown in Fig. 3 it is substantially parallel with the front face of the latch bar 57 against which it rests. When a lever 50 is depressed, the latch bar 57 rides on the beveled edge of the projection 62 until the lever is substantially in seated position with reference to the corresponding control member 14. This is the position corresponding to that illustrated in Fig. 3 and in this position the spring 59 pulls downwardly on the latching bar 57 to drop it behind the projection 62. The tension of the spring 56 on the lever tends to hold the straight face of the projection 62 in engagement with the front face of the latch bar 57. The depressed position of a lever 50 is maintained until it is desired to tune the radio receiver to another station by pushing another button 51. When this is done the latch bar is raised by riding upwardly on the beveled face on the projection 62 of the newly operated lever 50 and as the bar reaches its peak position the formerly depressed lever under tension of spring 56 is pivoted upwardly to idle position.

The number of stations to which a receiver can be turned automatically is limited to the number of control units including a lever and control member. If it is desired to tune the radio receiver to a station other than that for which the control units are set, this must be done by rotating the manual tuning knob 28. An extension 63 is provided on the latch bar 57 on the outside of the frame plate 11 to cooperate with the friction varying and tuning structure including the control knob 28, and also to operate with a latching function. The extension 63 includes an integral arm 64 (Fig. 6) lying above the shaft 27 and in alignment therewith. The arm 64 includes a latching tooth 66 extending downwardly toward the shaft 27 and having a beveled edge on the front thereof and a vertical edge on the back thereof adjacent a recess 67 extending from the lower edge of the arm. When the control knob 28 and the associated shaft 27 is pressed inwardly from a friction varying position as shown in Fig. 4, or in idle position as shown in Fig. 5, to a manual tuning position as shown in Fig. 6, the beveled edge of the metal disc 46 engages the beveled front edge of the tooth 66 to raise the arm until the disc is in registry with the recess 67, in which position the flat front face of the metal disc 46 is in engagement with the vertical rear edge of the tooth 66. The tooth 66 is so positioned that when the

disc 46 is engaged as described, the rubber disc 44 is in frictional engagement with the flange 41 on the tuning wheel 33. This position and the subsequent operation have been heretofore described.

As the knob 28 and associated shaft are being pushed into the position of Fig. 6, the arm 64 is raised to raise the latch bar 57 in the same manner as that accomplished when a lever 50 is depressed, as described above. Thus when the knob 28 is being rotated for manual tuning of the condenser, the levers 50 are all in idle position with the rollers 53 thereon spaced from the path of rotation of the control members 14 sufficiently so that there will be no engagement therewith to stop the rotation of the shaft 13.

Similarly when the knob 28 is in manual tuning position as illustrated in Fig. 6, and it is desired to automatically tune the condenser to one of the predetermined positions represented by the levers 50, upon depressing a selector lever, the latch bar 57 is raised in the manner described, and the knob 28 and shaft 27 under pressure from the coil spring 69 carried on the shaft 27 intermediate the knob 28 and a bushing 71, are pressed outwardly to the idle position of Fig. 5. In this position the rubber disc 44 is out of engagement with the wheel 33 and the shaft 13 may be rotated by movement of a lever 50 without at the same time rotating the shaft 27 and knob 28 structure which would put an additional load on the shaft 13.

The embodiment of my invention illustrated in Figs. 1 to 6 is normally employed where it is necessary or desirable to accomplish manual tuning and frictional pressure variation from the front of the radio receiver cabinet rather than from the end thereof. Where it is desired to manually tune the condenser 12 throughout the effective range thereof, and change the frictional pressure on the control apparatus, this may be accomplished by the modification shown in Fig. 7. This structure comprises an internally threaded gear 74 threadedly secured on the threaded portion of the shaft 13' corresponding to the shaft 13 of Fig. 1, and carrying the control members 14 thereon in the identical manner previously described. The hub for the gear 74 extends through an aperture in the end plate 11' of the tuner frame and serves to support the shaft 13' therein. The threaded gear 74 is operatively connected with the axially slidabie control member assembly. A rotatable knob 76 is frictionally retained on the outer end 77 of the shaft 13', with such end of such a configuration as to retain the knob against rotation. The stub shaft for the knob 76 extends through an aperture in the end wall 78 of the radio receiver cabinet. A pinion gear 79 for meshing with the gear 74 is secured to a stub shaft 81 journaled in the end plate 11' which also extends through the end wall 78 of the receiver cabinet. A spring 82 on the stub shaft 81 intermediate a fixed washer and the end plate 11', acts to normally press the shaft 81 outwardly so that the gear 79 is out of mesh with the gear 74.

In the illustration of Fig. 7 the structure is shown with the control assembly in reduced friction position. The spring washer 22 is in open position and the frictional pressure is reduced intermediate the control members 14 and their corresponding washers so that the control members can be individually angularly adjusted as previously described. Assuming that the control members are set as desired, and the fric-

tional pressure is to be increased on the members 14, the shaft 13' is turned in a clockwise or counterclockwise direction depending upon the direction of the threads on the gear 74 and the shaft 13' until the stop arm 83 (Fig. 1) keyed to the rotary shaft engages one of the two stop lugs 84 stamped out of the end plate 10 and positioned to correspond with the limits of rotation for the tuning condenser 12. The shaft 13' cannot rotate further beyond the engaged position of the stop arm 83 and a lug 84, and the knob 76 is then slipped off the shaft 13' and placed over a similarly shaped end on the stub shaft 81 for the pinion gear 79. Merely for purposes of illustration the pinion gear 79 is shown in Fig. 7 in mesh with the gear 74, but it is normally pressed outwardly by the spring 82. Normally the shaft 81 would be pushed inwardly to mesh position and then rotating the knob 76, the gear 79, and consequently the gear 14, would be rotated in a direction such as to move the gear 74 axially to the left on the shaft 13' as viewed in Fig. 7. This, of course, would move the entire control member assembly to the left as previously described until the desired frictional pressure was obtained in such assembly. The knob 76 may then be pulled from the shaft 81, and replaced on the shaft 13' and the stub shaft 81 under pressure from the spring 82 will spring outwardly to separate the gears 79 and 74.

To reduce the frictional pressure in the control assembly, the same procedure is followed except that the shaft 13' is originally rotated in the opposite direction to bring the stop arm 83 against the opposite lug 84 from that which was utilized for the friction increasing operation. The tuning condenser 12 in the embodiment of Fig. 7 is normally moved throughout its effective range by means of the knob 76 directly on the shaft 13', although, of course, this can be accomplished through the gear 79.

A still further modification of the invention is illustrated in Fig. 8, with friction varying structure designed to be adapted for use with the control member assembly illustrated in Fig. 1 as well as the condenser, tuner frame, and the like therewith. In the structure of Fig. 8 an internally threaded gear 86 is threadably secured on the shaft 13'' in a manner similar to the corresponding gear 24 in Fig. 1. The hub 87 for the gear extends through the end plate 11 for operative connection with a control member assembly as shown in Fig. 1. When it is desired to change the axial position of the gear 86 in order to vary the frictional pressure on the control members 14, as previously described, a lever 88 pivotally mounted on the end plate 11 and extending either through the back 89 of the cabinet for the receiver, or if desired through the front wall thereof, is depressed to the position shown in Fig. 8. In this position a tooth 91 on the inner end of the lever engages a tooth in the gear 86. The shaft 13'' is then rotated by a right-angled drive system operated from the front of the radio receiver cabinet, or by a knob as 90 (shown in dotted lines) similar to that in Fig. 7 at the end wall of the cabinet, and the relative axial position between the gear 86 and shaft 13'' is changed. When the operator removes his finger from the lever 88, the spring 92 pulls it downwardly out of connection with the gear 86 and the latter is free to turn with the shaft 13''.

In the modification illustrated in Fig. 9 an internally threaded sleeve or bushing 93 is threadably secured on the end of the rotary tun-

ing shaft 13". The sleeve 93 is in operative connection with the axially movable control assembly including control members 14 and the associated structure as described with reference to the device of Fig. 1. The sleeve 93 likewise acts to support the shaft 13" in the end wall 11 of the tuner frame. A knob 94, or similar finger engaging member, may be slipped over the sleeve 93 and rigidly secured thereto by a set screw 96 or the like. A pin 97 is then inserted through a corresponding aperture in the ends of the shaft 13" and secured therein against removal. As illustrated in Fig. 9, the structure is in partially decreased frictional pressure position. Before adjusting the sleeve 93 and its associated knob 94 to the position illustrated, the shaft 13" is rotated in one direction or the other, depending upon the thread upon the shaft 13" and the sleeve 93, until the stop arm 83 engages a corresponding stop lug 84 as described above. The rotation of the knob 94 is then continued in the same direction, but with the shaft 13" maintained against rotation the sleeve 93 will be threadably adjustably moved to the right to permit the control assembly to open up and the frictional pressure to be decreased. This rotation of the knob 94 is continued until the shoulder 98 at the end of the sleeve 93 is in frictional engagement with a pin 97, or the like, and normally it is desired that this engagement be tight. This causes the sleeve 93 and knob 94 to be locked with the shaft 13" and such shaft may then be rotated in the opposite direction by the knob to adjust it to a predetermined angular position corresponding to a desired tuning position for the condenser 12 on the shaft 13". The sleeve 93, of course, extends through a side wall 98 of the radio receiver cabinet housing the control apparatus.

When all of the control members 14 have been set to desired tuning positions, the knob 94 may be rotated to rotate the shaft and bring the stop arm 83 keyed thereto against the opposite stop lug 84 to that mentioned above. With the shaft thus held against rotation the rotation of the knob 94 in the same direction is continued to threadably adjust the sleeve 93 to the left as shown in Fig. 9, and thus frictionally lock such sleeve in operative connection with the control assembly. This assembly, in the meantime, has been compressed until the control members 14 are frictionally engaged against angular rotation with reference to the shaft 13". After this operation is completed the entire control apparatus is in condition to be operated either automatically by levers as 50, or the tuning shaft 13" may be rotated throughout its entire range by the knob 94.

The disclosures of this application are illustrative and the invention is not to be limited by them. In fact, if modifications or improvements are not at once obvious, they may be devised in the course of time to make additional use of the broad ideas taught and covered by this application. The claims are intended to point out novel features and not to limit the invention except as may be required by the prior art.

I claim:

1. Control apparatus for a radio receiver including in combination a rotary shaft, a frame 70 for carrying said shaft, a plurality of control members supported on said shaft, means axially movable with said control members on said shaft for normally frictionally retaining the members against angular rotation on said rotary shaft, 75

means for varying the friction on the control members on the rotary shaft and operatively connected therewith including a toothed wheel threadably secured on said rotary shaft, a second toothed wheel rotatably supported on said frame spaced from said rotary shaft and adapted for meshing with said first toothed wheel when the friction is varied and normally out of mesh at other times, finger engaging means for operative connection selectively with either said rotary shaft or said second toothed wheel for directly rotating either one or the other, and means for retaining the rotary shaft stationary while said first toothed wheel is rotated by the rotation of the second toothed wheel in mesh therewith.

2. In a tuning device for a radio receiver, a rotatable shaft having a thread portion at one end thereof, means for limiting rotation of said shaft to a predetermined path less than 360°, a plurality of tuning selector elements on said shaft normally frictionally retained against rotation thereon, means for varying the frictional pressure on said elements with said shaft stopped at one of the limit points in said predetermined path, said means including a toothed wheel threadably supported at the thread portion on said shaft, and an independently supported rotatable member for engaging said toothed wheel to rotate the same on the shaft with the shaft in said stopped position to vary the axial position of said toothed wheel on said shaft, and a finger engaging member for operative connection either with said shaft or said rotatable member for rotating the same.

3. Control apparatus for a radio receiver including in combination a rotary shaft, a plurality of control members supported on said shaft and normally frictionally retained against angular rotation relative to said rotary shaft, friction varying means operatively connected with said control members including an internally threaded unit threadably carried on said rotary shaft and axially adjustable thereon, a pivotally supported lever adjacent said unit having a projection on one end thereof and a finger-engaging portion on the other end thereof, with said lever adapted to be depressed for engaging said projection with a corresponding engageable portion on said unit to retain the unit in a stationary position, and means for rotating the shaft while the unit is held to change the relative axial position between the shaft and said unit.

4. Control apparatus for a radio receiver including in combination a rotary shaft, a plurality of control members supported on said shaft and normally frictionally retained against angular rotation relative to said rotary shaft, means for varying the frictional pressure on said control members, said varying means including an internally threaded gear threadably carried on said rotary shaft and axially adjustable thereon in operative connection with said control members, means rigidly secured to said shaft adjacent said gear on the side thereof opposite the control members, means for holding said rigid means and said shaft stationary while rotating said gear, said holding means including a rotatable and longitudinally movable shaft, a toothed member non-axially movable on said longitudinally movable shaft and with said shaft rotatable relative thereto, said toothed member adapted to engage said rigid means on one side, a stationary locking member on the other side of said toothed member to hold said toothed mem-

ber stationary together with said rigid means and rotary shaft, and a gear fixedly secured to said longitudinally movable shaft for engagement with said threaded gear to rotate the latter and axially move the threaded gear relative to the rotary shaft.

5. In control apparatus, a rotary shaft, a plurality of frictionally engaged control members on said shaft, and means in operative connection with said control members for varying the frictional pressure thereon, said means including a toothed member threadably carried on said rotary shaft, a second shaft at right angles to said rotary shaft supported for axial and rotary movement, means fixed on said second shaft for selective meshing engagement with said toothed member to axially move the latter relative to said rotary shaft upon rotation of said second shaft, and means on said second shaft for operative connection with said rotary shaft to retain the latter stationary but permit the second shaft to rotate in said means on said second shaft to axially move said toothed member.

6. Control apparatus for a radio receiver including in combination, a rotary shaft, a plurality of control members supported on said shaft and normally frictionally retained thereon against angular adjustment relative thereto, unit means having means for rotating said shaft for tuning control over the tuning range of the apparatus, a plurality of selector means corresponding in number to said control members with each selector means selectively engageable with a corresponding control member to move the control member to a predetermined tuning position, pivotally supported latch means for retaining a moved selector means substantially in tuned position, and being common to all of said selector means, with each of said selector means having a latching portion thereon engageable with said latch means to move the same to latching position, said unit means being longitudinally movable and including a latching member operatively engageable with said latch means for retaining said unit means in operative position for rotating said shaft, and with said latching means being releasable from a latched selector means or the latched unit means upon subsequent movement of another selector means.

7. Control apparatus for a radio receiver including in combination a rotary shaft, a plurality of control members supported on said shaft and normally frictionally retained thereon against angular adjustment relative thereto, combination manual tuning and friction varying means operatively connected with said control members and said rotary shaft, with said combination means including a toothed member threadably carried on said rotary shaft for axial adjustment thereon, a tuning wheel fixedly secured on said rotary shaft adjacent said toothed member for manual rotation of said rotary shaft, and a second shaft positioned for axial and rotatable movement at right angles to said rotary shaft having a gear thereon for operating engagement with said toothed member and a driving member thereon for operating engagement with said tuning wheel to manually rotate the latter to rotate the rotary shaft therewith, with said second shaft being axially movable to bring one of said structures as between said gear and said driving member into an operating position, movable selector members for selectively moving said control members to automatically move said

rotary shaft, and latching means for holding a movable selector member in moved position and holding the driving member in engagement with the tuning wheel depending upon whether the rotary shaft is automatically rotated or manually rotated.

8. Control apparatus for a radio receiver, including rotary control means, means for rotating said control means to predetermined tuned positions, and means for rotating said control means independently of said first mentioned rotating means to all tuned positions over the range of signal frequencies received by a radio receiver with such apparatus, said first mentioned rotating means including a plurality of selector members for selected operative connection with said rotary control means, said second mentioned rotating means including a tuning wheel fixedly secured on said rotary control means and a friction unit having a friction disc for selected frictional engagement with said tuning wheel to rotate the latter, and movable latching means operatively common to said selector members and said friction disc for selectively latching either a selector member or said friction disc substantially in operated position.

9. Tuning apparatus for a radio receiver including in combination of a rotary shaft structure, a plurality of control members supported on said shaft and normally frictionally retained against angular rotation relative thereto, a friction varying unit structure adjustably secured on said shaft in operative connection with said control members, manually operated spring-tensioned means normally independent of said friction varying unit structure and said rotary shaft structure operatively connectible with one of said two structures with one of said two structures being maintained stationary, while the other structure is rotated to change the relative axial position of said friction varying unit structure and said rotary shaft structure, and means for manually rotating said rotary shaft structure to change the control position of said control members thereon, with said spring-tensioned means being out of operative connection engagement with said friction varying unit structure during such manually rotating operation.

10. Tuning apparatus for a radio receiver including in combination a rotary shaft, a plurality of control members supported on said shaft and normally frictionally retained against angular rotation relative thereto, a friction varying unit adjustably secured on said shaft in operative connection with said control members, manually operated spring-tensioned means normally independent of said friction varying unit manually movable into operative connection with said friction varying unit and maintainable in said operative connection while the relative axial position of the shaft and friction unit is changed to change the friction exerted by said unit on said control members, and means for manually rotating said shaft to change the control position of said control members, with said spring-tensioned means being out of engagement with said friction unit during such manual rotational operation for the control members.

11. Tuning apparatus for a radio receiver including a rotary shaft, stop means for limiting the rotation of said shaft, a plurality of control members supported on said shaft and normally frictionally retained against rotation relative thereto, a friction member operatively connected with said control members and mounted on said

shaft for relative axial movement therewith to vary the frictional pressure on said control members, hand-engaged rotating means normally independent of said friction member but operatively connectible with said friction member to adjust said friction member when the rotary shaft is stopped by said stop means, driven means secured to said shaft independently of said friction member and always out of engagement with said friction member operatively connecting said hand-engaged means and said shaft during a setting operation of a control member when said hand-engaged means is entirely out of operative connection with said friction member and is acting to rotate said shaft to change the relative position of a control member and said shaft for tuning setting and a driving member on said hand-engaged means engaging said driven means to accomplish the operative connection between said hand-engaged means and said shaft.

12. Tuning apparatus for a radio receiver including in combination a rotary shaft, frame means for supporting said shaft, a stop on said shaft and corresponding stop means on said frame for engagement with the stop for limiting the rotary movement of the shaft, a plurality of control members supported on said shaft and normally frictionally retained against angular rotation relative to said shaft, means for varying the friction on the control members, including an internally threaded axially adjustable member on said shaft operatively connected with said control members, finger-engaging means for operative connection with said threaded member to rotate said member while said shaft is held against rotation by said stop and said stop means to axially adjust said threaded member, and means for operatively connecting said finger-engaging means with said shaft independent of said threaded member, with said operative connection being made at a time when the finger-engaging means is entirely out of connection with said threaded member to rotate said shaft upon rotation of said finger-engaging means to change the angular relation between the control member and said shaft for a predetermined tuning setting of said control member.

13. In a tuning device for a radio receiver, a rotatable shaft having a thread portion at one end thereof, means for limiting rotation of said shaft to a predetermined path less than 360°, a plurality of tuning control members on said shaft normally frictionally retained against rotation thereon, means for varying the frictional pressure on said members with said shaft stopped at one of the limit points in said predetermined path, said means including a first gear member threadably supported at the thread portion on said shaft, a second gear member rotatably supported independently of said shaft for engaging said first gear member to rotate the same on the shaft with the shaft in said stopped position to vary the axial position of said first gear member on said shaft, and knob-like means for separable operative connection either with said shaft or said second gear member for rotating the same.

14. In control apparatus for a radio receiver having a rotary shaft, and a plurality of control members supported on said shaft, the combination of hand-tuning means for rotating said shaft to tuning positions over the tuning range of the apparatus, a plurality of selector units corresponding to said control members, with each selector unit adapted for selective engagement with a corresponding control member to move the

5 latter to a predetermined tuned position, movable latching means operatively common to all of said selector units and said hand-tuning means for releasably retaining a moved selector member substantially in tuned position and said hand-tuning means in operating position, with each of said selector units having a latching portion thereon adapted to engage said movable latching means to move the same to latching position, said hand-tuning means including a linearly movable shaft and a latch-moving portion with the latter engaging the latching means for retaining the hand-tuning means in operative position for rotating the linear shaft to in turn move the rotary shaft, and with said movable latching means normally being released from a latched selector unit or the latched hand-tuning means upon subsequent movement of another selector unit.

15. In control apparatus for a radio receiver 20 having a rotary shaft, a plurality of control members supported on said shaft, and a tuning member operatively connected to said rotary shaft, the combination of hand-tuning means for rotating said shaft to all tuning positions over the 25 tuning range of the apparatus, a plurality of selector units corresponding to said control member, with each selector unit adapted for selective engagement with a corresponding control member to move the latter to a predetermined tuned position, movable latching means operatively common to all of said selector units and said hand-tuning means for releasably retaining a moved selector member substantially in tuned position and said hand-tuning means in operating position, with each of said selector units having a latching portion thereon adapted to engage said movable latching means to move the same to a latching position, said hand-tuning means including a linearly movable and rotatably supported rotating member, and bi-part 35 means supported on said linear member, said bi-part means having a driving portion for driving engagement with the tuning member operatively connected with the rotary shaft, and a beveled 40 latch moving portion, with the latter engaging the latching means for retaining the hand-tuning means in operating position to rotate the linear member and the rotary shaft, and with said movable latching means normally being released from a latched selector unit or the latched hand-tuning means upon subsequent movement of another selector unit.

16. In control apparatus for a radio receiver 45 having rotary control means, with means for rotating the control means to predetermined tuned positions, and means normally independent of the first-mentioned rotating means for rotating the control means substantially over the tuning range of the receiver, the combination of a plurality of selector means in said first-mentioned rotating means, selectively connectible with said rotary control means, a rotatable driven member and a rotatable driving member selectively engageable therewith in said second-mentioned rotating means, hand-operated means operatively connected with said rotatable driving member to selectively move said driving member into engagement with said driven member, and movable latching means operatively common to the selector means and the driving member for selectively retaining a selector means in operative position relative to said rotary control means and the driving member in operative position relative to said driven member.
